UNITED STATES PATENT OFFICE.

PALMER CLINGMAN, OF NEW YORK, N. Y.

ELECTRICAL CONDUCTOR.

1,122,863.

Specification of Letters Patent. Patented Dec. 29, 1914.

Application filed June 29, 1914. Serial No. 847,912.

To all whom it may concern:

Be it known that I, PALMER CLINGMAN, a citizen of the United States of America, residing at Broadway, in the county of 5 Queens, city of New York, State of New York, have invented certain new and useful Improvements in Electrical Conductors, of which the following is a specification.

My invention relates to electrical conductors and particularly to those which are employed to transmit high potential currents such as are employed in electric train service, and it consists primarily, in a gradually deflecting approach to a section insulator, 15 also in a switch for closing the circuit when that is desired.

Figure 1, represents a side view of an insulating break in a trolley wire, provided with parts of approaches embodying my invention. Fig. 2, shows a further portion of such an approach and of the main conductor. Fig. 3, is a plan view of the device (though not to scale), parts being omitted to more clearly exhibit the remainder. Fig. 25 4, is a side view of the insulator for supporting the switch, the insulator support and the key of the switch. Fig. 5, is a top view of the said support for the switch devices. Fig. 6, is a vertical cross-sectional view of the clamp or clip I sometimes employ to support the trolley wire or main conductor and to connect it and the T iron which I prefer to employ for the approach.

In high tension work, it is usual to break 35 the conductor 1, 2, into sections and to connect the sections, physically, by a wooden insulator 3, about 6 feet long. With a trolley system thus constructed, there is a physical shock attendant upon the engaging of 40 the moving pantograph shoe with the inflexible insulator. To avoid this shock, I have devised the approach, one embodiment of which is here shown. First I provide, preferably, two long light T irons (though 45 I do not limit myself to T irons). The ends of the T irons 4, 5, which project one past the other, I form with a gradual curve, opposite the wooden insulator 3. These irons may be about 30 feet long, though I do not 50 limit myself to any specific dimensions, but I prefer to have them long enough to project well past each other and to reach back to points on the main conductor sufficiently distant from the insulator connection to insure 55 that the conductor, at that point, shall yield easily to the flexing attendant upon

the pressure of the pantograph shoe against it as the car proceeds.

The hanger for supporting the conductor and the T iron at the point of connection, 60 may be similar to that shown at 6 in Fig. 6, provided with a body 6, pierced to receive a suspending rod, lugs 7, 8, one removable and held by a screw or bolt 9, which the body 6 is apertured to receive, and another 65 bolt 10 which holds the T iron 5, to the main conductor 2. At this initial point of suspension, the T iron is secured with its bearing face above (or below if an overrunning shoe is used) the level of the bearing 70 face of the conductor 2, but so set that its bearing face quickly comes to and then gradually extends below (or above) the level of said bearing face of the main conductor, so that, at the break and where the 75 irons project past each other, their bearing faces are considerably below (or above) the level of the bearing face of the main conductors 1, 2, as plainly seen in Fig. 1, that is they are between the bearing face of the 80 main conductor and the track on which the vehicle is intended to run, if the bearing face of the main conductor is on the side toward the track, but if the said bearing face of the main conductor is on the opposite side to that toward the track, as it would be with an over-running shoe, then the bearing faces of the T iron approaches where they overlap, would be farther from the 85 track than the bearing face of the main conductor. In either case it is farther from the center or axis of that main conductor, in a line extended from that center or axis toward and beyond its bearing face, than is 90 said bearing face itself. I call both of these 95 positions, "within the line of the bearing face of the main conductor," as they are within the space which would lie between that bearing face of the main conductor and the bearing face of the shoe, when it had 100 run up (or down) on the bearing face of the T iron approach.

The main conductors and consequently the T irons also, are usually suspended from a so-called messenger wire 11, by means of 105 hanger rods 12, 14, etc., and there may be as many of these as are desired. I also sometimes provide supplemental hanger rods, 15, etc., for suspending the T irons, all of such rods being so connected as to 110 permit the T irons to lift slightly, but readily, under the stress of the pressure of the

pantograph shoe. I also preferably provide stiff springs 16 17, secured to the insulator fixtures or connections 18, 19, to aid in supporting the T irons, and these springs 5 and the T irons themselves are deflected, one to the left and the other to the right, so that at the line where they project one (4) past the other (5), they shall be well separated,—for high potentials about 18 inches. Supporting rods 20, 21, are provided for connecting the T irons to these spring supports 16, 17. Gravity might be sufficient to hold the T irons to position, but when very light irons are used I sometimes provide 10 springs 22, 23, secured to the fixtures 18, 19, and to the T irons 4, 5, with their stress opposing any movement toward the line of the main conductor, to insure that the T irons shall be held to place.

20 The shoe of the pantograph is wide enough to touch both T irons 4 and 5, when it reaches the point where they register one with another, but of course it will bear upon only one when approaching the break and 25 upon the other when receding therefrom. This might tend to tip the device if there were nothing to prevent, so I connect the rod 14, rigidly to the insulator 3, or its fixture, and then to the passenger wire 11, thus providing 30 a sufficient resistance to this tilting action. There may be another such rod extended from the other end of the insulator or its fixture, to the messenger wire above it.

Since it is sometimes desirable to close 35 the circuit across the break, I provide a switch for that purpose. It consists of a support 24, secured to insulator 3, about 18 inches from the end. In this support, I mount another insulator 27, on a shaft or 40 rod 25, with a polygonal shaped head 26, and from the insulator 27, (usually porcelain), I extend a switch arm 28, long enough to reach and make contact with a contact post 29, preferably mounted upon the fixture 45 18. The shaft 25, is provided with a key 30, adapted to fit into key-ways 31 and 32, formed in the support 24, and from the switch arm 28, I lead a circuit wire 33, back to the main conductor 2. The extra insulator 27, is usually provided to insure that 50 there shall be no short circuiting when maintenance of the break in the circuit is desired. Now if I desire to close the circuit, I raise a rod or pole, provided with a socket wrench, 55 till the socket engages the head 26, press it upward until I raise the key 30 out of the key-way 32, turn it until the key registers with key-way 31, and then lower it into engagement therewith, the parts having 60 been so proportioned that the arm 28, will then have made contact with the contact post 29.

The approaches, as will be noted, are not under any tension, as is the main conductor 65 1, 2 and the insulator 3, consequently said

approaches may yield slightly, but readily and without undue resistance, in response to the pressure of the pantograph shoe. As this moving pantograph shoe approaches the break in the section, it will ride upon the T 70 iron and then off from the main conductor, being gradually separated from that till it reaches and makes contact with the T iron upon the farther side of the break and proceeds along that to the point where the other 75 section of the main conductor lies even with the bearing face of said second approach iron. It will reach the second approach iron before it has broken contact from the first approach iron, consequently the circuit 80 from the moving vehicle to the conductor remains closed during the passage of the pantograph shoe over the space occupied by the insulator 3, but the shock of contact therewith will have been avoided.

What I claim and desire to secure by Letters-Patent, is:—

1. The combination with an electric conductor and an insulator interposed between sections of the main conductor, of a comparatively rigid conductor connected to one section of the main conductor, at a point some distance from the insulator and extending, on an easy grade, to a point beyond the nearest end of the insulator, said second conductor being so set that it shall have its bearing face level with the bearing face of the main conductor at a point preceding the proximate end of the section and, at a point succeeding said end of the main conductor 90 section, said bearing face of the second conductor shall be within the line of the bearing face of the main conductor, all substantially as set forth.

2. The combination with an electric conductor and an insulator, interposed between sections of the main conductor, of a pair of comparatively rigid conductors connected to the respective sections of the main conductor at points some distance from the insulator, and extending, on an easy grade, toward each other and to points respectively beyond the nearest end of the insulator, said second conductors being so set that they 100 shall have their bearing faces level with the bearing faces of the main conductor at points respectively preceding the proximate ends of the sections and, at points succeeding said ends of the main conductor sections, said bearing faces of the said second conductors shall be within the line of the bearing face of the main conductor, all substantially as set forth.

3. The combination with an electric conductor and an insulator interposed between sections of the main conductor, of a pair of comparatively rigid conductors connected to the respective sections of the main conductor at points some distance from the insulator, and extending toward each other, one be- 110 120 130

yond the line of the other, on an easy grade, from a level other than that of the bearing face of the main conductor, to, across and beyond the plane of the bearing face of said 5 main conductor and to points respectively beyond the nearest end of the insulator, all substantially as set forth.

4. The combination with an electric conductor and an insulator interposed between 10 sections of the main conductor, of a light T-iron connected to one section of the main conductor at a point some distance from the insulator and extending, on an easy grade, to a point beyond the nearest end of the insulator, said second conductor being so set 15 that it shall have its bearing face level with the bearing face of the main conductor at a point preceding the proximate end of the section and, at a point succeeding said end 20 of the main conductor section, said bearing face of the second conductor shall be within the line of the bearing face of the main conductor, all substantially as set forth.

5. The combination with an electric conductor and an insulator interposed between 25 sections of the main conductor, of a comparatively rigid conductor connected to one section of the main conductor at a point some distance from the insulator and extending, on an easy grade, to a point beyond the nearest end of the insulator, said second conductor being so set that it shall have its bearing face level with the bearing face of the main conductor at a point preceding the 30 proximate end of the section and, at a point succeeding said end of the main conductor section, said bearing face of the second conductor shall be within the line of the bearing face of the main conductor, together with a 35 spring interposed between the insulator and the said second conductor, all substantially as set forth.

6. The combination with an electric conductor and an insulator interposed between 40 sections of the main conductor, of a second 45

conductor connected to one section of the main conductor at a point some distance from the insulator and extending, on an easy grade, to a point beyond the nearest end of the insulator, said second conductor being 50 so set that it shall have its bearing face level with the bearing face of the main conductor at a point preceding the proximate end of the section and, at a point succeeding said end of the main conductor section, said 55 bearing face of the second conductor shall be within the line of the bearing face of the main conductor, together with a suspending spring and a depressing spring interposed between the said insulator and said 60 second conductor, all substantially as set forth.

7. The combination with an electric conductor and an insulator interposed between sections of said main conductor, of a second 65 conductor connected to one section of the main conductor at a point some distance from the insulator and extending, on an easy grade, to a point beyond the nearest end of the insulator, said second conductor 70 being so set that it shall have its bearing face level with the bearing face of the main conductor at a point preceding the proximate end of the main conductor section and, at a point succeeding said end of the main 75 conductor section, said bearing face of the second conductor shall be within the line of the bearing face of the main conductor, together with means, substantially as set forth, for holding said second conductor in a given 80 vertical plane, all substantially as set forth.

In testimony whereof, I have signed my name to this specification in the presence of two subscribing witnesses, this 25th day of June, 1914.

PALMER CLINGMAN.
